United States Patent Office

Des. 181,082

Patented Sept. 24, 1957

181,082

JACKET

Louis Warmflash, Elizabeth, N. J., assignor to Blue Bell, Inc., Greensboro, N. C., a corporation of North Carolina

Substitute of abandoned application Serial No. 39,328, December 13, 1955. This application December 13, 1956, Serial No. 44,196

Term of patent 14 years

(Cl. D3—4)

Fig. 1.

Fig. 2.

Fig. 3.

Fig. 4.

Fig. 1 is a front view of a jacket showing my new design;

Fig. 2 is an enlarged sectional view thereof taken on line 2—2 of Fig. 1;

Fig. 3 is a rear view of the jacket shown in Fig. 1; and

Fig. 4 is an enlarged sectional view thereof taken on line 4—4 of Fig. 3.

This application is a substitute for my prior application D. 39,328 which was filed on December 13, 1955, and which is now abandoned.

I claim:

The ornamental design for a jacket, as shown and described.
